CLAIM

The ornamental design for a smart pool cleaner, as shown and described.

DESCRIPTION

FIG. 1 is a front, left and top perspective view of a smart pool cleaner, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the smart pool cleaner that form no part of the claimed design.

1 Claim, 8 Drawing Sheets
